UNITED STATES PATENT OFFICE.

ARTHUR MAYER, OF RICHMOND HILL, NEW YORK, ASSIGNOR TO EDWARD V. HARRIS,
FORD, INC., A CORPORATION OF NEW YORK.

BRACKETS.

1,397,105.

specification of Letters Patent.

Patented Nov. 15, 1921.

Application filed March 13, 1918. Serial No. 221,582.

To all whom it may concern:

Be it known that I, ARTHUR MAYER, a citizen of the United States, residing at Richmond Hill, in the county of Queens and State of New York, have invented certain new and useful Improvements in Brackets, of which the following is a specification.

This invention relates to an improvement in brackets and while it is adapted for many uses, is especially well adapted for use in maintaining bumpers in position on a vehicle. The advantages of the present invention reside in the simplicity and strength of the device and its adaptability for application both to the bumper and to the car in various positions to suit different makes of cars and various makes of bumpers. I have shown the device applied in various positions, but it is to be understood that it may be capable of other uses than those illustrated.

In the accompanying drawings

Figure 1 shows in perspective a bumper in place on the horns of an automobile and held in position by the present invention.

Fig. 2 is a plan of the device.

Fig. 3 is an enlarged view of the horn of a vehicle, showing the bracket applied thereto in a position similar to that shown in Fig. 1.

Fig. 4 is a sectional elevational view of the bracket in place.

Fig. 5 shows the bracket in position turned end for end to the showing of Fig. 3.

Fig. 6 shows the bracket turned upside down relative to the position shown in Fig. 5.

Fig. 7 shows the bracket turned end for end relative to the showing in Fig. 6.

Fig. 8 shows the bracket attached to the bumper and secured to the upper part of the horn of the vehicle.

Fig. 9 shows the bracket in a similar position to that of Fig. 8, but turned end for end.

In Fig. 10 the bracket is shown upside down relative to the position shown in Fig. 9.

Fig. 11 shows the bracket turned end for end as compared with the showing in Fig. 10.

In Fig. 12 the bracket is shown secured to the underside of the horn of the vehicle.

Fig. 13 the bracket is turned end for end from the showing of Fig. 12.

Fig. 14 the bracket is shown upside down

from the position shown in Fig. 12, but secured to the underside of the horn of the vehicle; and

Fig. 15 the bracket is shown turned end for end relatively to the showing in Fig. 14.

Referring to the drawings in detail, I designate an automobile bumper (see Fig. 1), held in place on the horns 2-2 of an automobile by a bracket 3, the latter being the device of the present invention. This bracket, which has been illustrated in various positions, comprises an integral member having an angular portion 4. A slot 5 is provided in the end of the angular portion 4 of the bracket for the reception of a U bolt 6 adapted to engage the horn 2. The bumper is secured to the bracket at two points by a bolt 7 and a hook bolt 8, the latter in Fig. 1 engaging the horn 2 of the vehicle. By reason of the slot 5 in the bracket the bumper may be adjusted vertically to suit various types of car. It is obvious that by reason of the makeup of the bracket the bumper will be held perfectly rigid when in position on the car, but may readily be detached therefrom or attached thereto. It will be obvious also that the bracket renders it possible to attach bumpers readily to any existing type of car, nor is it necessary that the bumper be attached to the horns of the car, as illustrated, but may be attached to any other part of the car that may be desired.

I have shown various applications of the bracket for illustrative purposes only. By reason of the simplicity of the present device, probably a detailed description of the various figures of the accompanying drawings is not necessary, but I will for the sake of clearness give a brief outline of the various applications of the bracket illustrated.

The figures so far referred to include 1, 2, 3 and 4. In Fig. 5 the bracket has been shown turned end for end from the position shown in Fig. 1, the bolt 8 passing through the slot 5, while the bolt 6 passes through the other end, both bolts engaging the horn 2 in the same manner as before.

In Fig. 6 the bracket has been turned upside down from the position shown in Fig. 5 and end for end from that of Fig. 3, the bolts 8 and 6 passing through the slot 5 and the other end of the bracket respectively.

In Fig. 7 the slotted end of the bracket is

secured directly to the bumper, the bolt 6 engaging the underside of the horn 2.

In Fig. 8 both ends of the bracket are secured to the upper side of the horn, the 5 angular portion 4 being secured to both horn and bumper, both bolts 6 and 8 being secured to the upper side of the horn.

Fig. 9 shows the bracket with the slotted end secured to the horn only, while the other 10 end of the bracket is secured to the upper side of the horn as well as to the bumper itself.

In Fig. 10 the slotted end is secured to the upper side of the horn, and to the 15 bumper, while the other end is secured to the upper side of the horn only.

In Fig. 11 the bracket is shown turned end for end from the position shown in Fig. 10, with the slotted end secured to the upper 20 side of the horn only, while the other end of the bracket is secured to the upper side of the horn as well as to the bumper.

In Fig. 12 the bracket has been shown secured to the underside of the horn with 25 the slotted end secured to both bumper and horn, while the other end is secured to the horn only.

Fig. 13 shows the bracket turned end for end from the showing of Fig. 12 with the 30 slotted end secured to the horn only, while the other end is secured to both horn and bumper.

In Fig. 14 the bracket is shown upside down from the position of Fig. 12 with the 35 slotted end secured to the horn only, while the other end is secured to the underside of the horn and bumper.

In Fig. 15 the bracket is shown in a position similar to Fig. 14, but is turned end 40 for end relatively thereto. In this figure the slotted end is secured to both the underside of the horn and the bumper, while the other end is secured to the horn only.

It will be apparent from the foregoing 45 that the bracket constituting the present invention is capable of numerous applications, all of which are of advantage under certain conditions. It will be understood, of course, that with some makes of automobiles 50 it would suffice to have the bracket applied, as shown in Figs. 1 to 7, inclusive, wherein the bracket has a bearing on both the upper and lower sides of the horn of the vehicle. In this position the bumper may be adjusted 55 vertically, however, to suit the particular make of car to which the bracket is applied. In other cases it may be desirable to have the bracket applied, as shown in Figs. 8 to 11, inclusive, wherein it has a bearing on 60 the upper side only of the horn of the vehicle. In this position, however, the bumper is adjustable vertically, as before. Under certain other conditions, it might be desirable to apply the bracket as shown in Figs. 65 12 to 15, inclusive, where it is secured to the

underside of the horn. This might probably be the case where it is desired to have the bumper set very low. In this position the bumper may be adjusted vertically also.

It will be apparent also from the foregoing description, the application of the bracket is exceedingly simple and may be accomplished without the use of any special tools and without the use of particularly skilled labor, all of which is of great advantage in devices of this character, as it is the aim of all manufacturers of accessories to keep the cost of the article itself as well as the cost of application down to a minimum.

I do not limit myself to the use of this particular type of bracket with automobile bumpers, of course, nor have I attempted to show all the various positions in which the bracket may be applied, but have merely 85 shown sufficient various applications of the bracket to illustrate its ready adaptability to numerous situations.

It will be apparent also from the foregoing that a bumper, for instance, secured 90 to a vehicle by my present invention, will be held rigidly in place by reason of the fact that two bearing surfaces have been provided for each end of the bumper, which, of course, will maintain the bumper always 95 rigidly in position on the vehicle. This holds true for any of the various applications of the bracket illustrated.

What I claim as new and desire to secure by Letters Patent of the United States, is: 100

1. As an article of manufacture, a bracket 105 for attaching a bumper to a vehicle comprising a substantially flat member having an angular portion, said bracket being adapted to lie against the web of a frame member of the vehicle whereby the attaching end of the bumper, the bracket and the web of the frame will occupy parallel planes.

2. As a new article of manufacture, a 110 bracket for attaching a bumper to the frame of a vehicle consisting of a flat plate in the form of an oblique angle having an elongated slot at one end, an aperture at the other end, and an aperture intermediate of its 115 ends, one of said apertures being adapted to receive means for attaching said bracket to a frame-member of the vehicle, the intermediate aperture being adapted to receive means for attaching the bumper to the 120 bracket, and the remaining aperture receiving means for connecting the bumper to the bracket and the bracket to said frame-member.

3. The combination with an automobile 125 bumper having a flat attaching portion and a frame-member of the vehicle, of a bracket for rigidly connecting said bumper to said frame-member, said bracket comprising a flat plate of an angular configuration 130

adapted to be positioned between the frame-member and the extension of the bumper, said plate having an elongated aperture in one end thereof, an aperture in the other 5 end, and an aperture intermediate of said end apertures, means located in one of said end apertures for engaging the frame-member of the vehicle, means located in the other end aperture for engaging the bumper 10 per extension and the frame-member respectively, and means seated in the intermediate aperture for connecting the extension of said bumper to said bracket.

4. The combination with an automobile 15 bumper having a flat attaching portion and a frame-member of the vehicle, of a bracket for rigidly connecting said bumper to said frame-member, said bracket comprising a flat plate of an angular configuration 20 adapted to be positioned between the frame-member and the extension of the bumper, said plate having an elongated aperture in one end thereof, an aperture in the other end, and an aperture intermediate of said 25 end apertures, means located in one of said end apertures for engaging the frame-member of the vehicle, means located in the other end aperture for engaging the bumper extension and the frame-member respectively, 30 and means seated in the intermediate aperture for connecting the extension of said bumper to said bracket, the plane of the bumper being adjustable relatively to the frame-member by the provision of the 35 elongated aperture in one end of said bracket.

5. As a new article of manufacture, a bracket for attaching a bumper to a vehicle comprising a substantially flat member in 40 the form of an oblique angle adapted to lie against the web of a frame-member of the vehicle and provided with an elongated aperture in one end thereof, an aperture in the other end of said bracket and an aperture intermediate of said end apertures, two of said apertures being adapted to receive means for fastening the bracket to

said frame-member and two of said apertures being adapted to receive means for fastening the bumper to the bracket. 50

6. A bracket for attaching a bumper to a vehicle comprising an angular plate adapted to lie against the web of a frame-member of the vehicle and provided with an aperture adjacent to each end thereof, 55 and an aperture intermediate of said end apertures, two of said apertures being adapted to receive means for fastening the bracket to said frame-member and two of said apertures being adapted to receive 60 means for fastening the bumper to the bracket.

7. The combination with an automobile bumper having a flat extension and a vehicle frame-member of a bracket for attaching 65 the bumper to the frame-member, said bracket comprising an angular plate adapted to lie against the web of the frame-member and provided with three apertures, one of which is elongated, and means located in said apertures for rigidly connecting the extension of said bumper to said frame through the medium of said bracket, two of said means engaging the bumper, 70 and two of said means engaging said frame-member. 75

8. The combination with an automobile bumper having a flat extension and a vehicle frame-member of a bracket for attaching the bumper to the frame-member, said bracket comprising an angular plate adapted to lie against the web of the frame-member and provided with three apertures, one of which is elongated, and means located in said apertures for rigidly 80 connecting the extension of said bumper to said frame through the medium of said bracket, two of said means engaging the bumper, and two of said means engaging 85 said frame-member, the plane of the bumper being adjustable relatively to said frame-member by the movement of one of said means within said elongated aperture. 90

ARTHUR MAYER.
